Primary Examiner — Carla J Wright(74) *Attorney, Agent, or Firm* — Georgi Korobanov(57) **CLAIM**

The ornamental design for a case for mobile phone, as shown and described.

DESCRIPTION

FIG. 1 is a bottom, front, right side perspective view of a case for mobile phone showing my new design;

FIG. 2 is a bottom, rear, left side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is an enlarged top plan view thereof; and,

FIG. 8 is an enlarged bottom plan view thereof.

The broken lines in the drawings illustrate portions of the case for mobile phone that form no part of the claimed design.

1 Claim, 6 Drawing Sheets(56)
